PRESSING IRON RACK

Charles R. Hawkins, Los Angeles, Calif.

Application December 9, 1946, Serial No. 715,095

2 Claims. (Cl. 248—117.1)

1

This invention relates to new and useful improvements and structural refinements in pressing iron racks, and the principal object of the invention is to provide a device of the character herein described which may be conveniently and effectively employed for supporting the iron when the same is not being used.

A further object of the invention is to provide a rack in which the iron may be readily applied and removed, and which, as a whole, may be conveniently mounted upon a wall, or other supporting structure.

Another object of the invention is to provide a rack which will firmly and securely retain the iron in position.

An additional object of the invention is to provide a rack which is simple in construction, pleasing in appearance and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a front elevation of the invention;

Figure 2 is a side elevation thereof, and

Figure 3 is a cross sectional view, taken substantially in the plane of the line 3—3 in Figure 1.

Like characters of reference are used to designate like parts in the specification and throughout the several views.

Referring now to the accompanying drawings in detail, the invention consists of a pressing iron rack designated generally by the reference character 5, the same embodying in its construction a pair of coacting shoes 6, configurated substantially as shown.

It will be noted that the shoes 6 are arcuated or concaved both longitudinally and transversely, each of the shoes consisting primarily of a tapered side wall 7 provided at one edge thereof with an inturned flange 8. These flanges are pivotally connected together adjacent the tapered ends of the shoes by a suitable rivet 9, as will be clearly apparent from the accompanying drawings.

Each of a pair of links 10 is pivotally connected at one end thereof by a further rivet 11 to

2

the remaining end of one of the flanges 8, the remaining ends of the links being pivoted by a rivet 12.

The latter is provided with a central aperture 5 adapted to receive a nail 13, or the like, whereby the entire assembly may be mounted in a substantially vertical position upon a wall 14. It will be also noted that a pad 15, formed from asbestos, or other non-combustible material is interposed between the rack and the wall, as is best shown in Figure 2.

The pad 15 is, of course, retained in position by the aforementioned nail 13 and it should be also noted that the shoes 6 and the links 10 are 15 "staggered," as it were, so that the inner heads of the rivets 9, 11 and 12 are "flush" with the outer surface of the asbestos pad. This arrangement is best illustrated in the accompanying Figure 3.

When the invention is placed in use, the pressing iron indicated by the phantom lines 15 is simply inserted between the shoes 6 and it will be found that the weight of the iron will cause the shoes and the associated links 10 to close, 25 so to speak, in the direction of the arrows 17, thereby firmly and securely clamping the iron between the shoes.

The provision of the pad 15 will, of course, prevent any heat such as the iron may possess 30 from being transmitted to the wall 14.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A pressing iron rack comprising in combination, a pair of shoes pivotally connected together at one end thereof and adapted to removably retain the iron therebetween, a pair of links, and a stationary pivot extending through one end portion of each of said links, the remaining ends 45 of said links being pivoted to said shoes.

2. A pressing iron rack comprising in combination, a pair of concave shoes pivotally connected together at one end thereof and adapted to removably receive the front end portion of the iron therebetween, a pair of links each pivoted at one end thereof to the remaining end of one of said shoes, and a stationary pivot extending through the remaining end portion of each of said links, said links and said shoes being suspended from said stationary pivot.

CHARLES R. HAWKINS.
